UNITED STATES PATENT OFFICE.

EDGAR M. CLARK, OF BROOKLYN, NEW YORK, ASSIGNOR TO A. S. FERGUSON COMPANY,
OF NEW YORK, N. Y., A CORPORATION OF NEW YORK.

GAME.

Application filed May 9, 1924. Serial No. 711,966.

To all whom it may concern:

Be it known that I, Edgar M. Clark, a citizen of the United States, and a resident of New York, borough of Brooklyn, in the county of Kings and State of New York, have invented certain new and useful Improvements in Games, of which the following is a specification.

This invention relates to games and particularly to that class thereof wherein one or more objects are removably mounted to be knocked down by missiles projected thereat. The object of my improvements is to provide a device or game of the character specified which may be collapsed for packing and shipping and easily erected into usable condition. Other features will appear later herein.

My improvements comprise features illustrated in their preferred embodiment in the drawing accompanying this specification, wherein:

Figure 1 is a front elevation of my improved game. Fig. 2 is a vertical section on line 2, 2 of Fig. 1. Fig. 3 is a top plan view. Fig. 4 is a sectional plan on line 4, 4 of Fig. 2. Fig. 5 is a perspective detail of my improvements. Figs. 1 and 2 are to one scale. Figs. 3 and 4 are to another scale about half that of the earlier figures. Fig. 5 is to a larger scale than any of the other figures.

For purposes of illustration, I have shown my improvements applied to a "bird game," wherein one or more images representing birds are perched upon a rail against a background which may be decorated to represent a landscape, such as a forest scene. The birds preferably employed are known articles of commerce and may be made of celluloid and preferably hollow. They are provided with a small claw member, as 3 to bird 5, and with a depending tail 6. Said birds are adapted to rest in upright position on rail 7 of front wall 8, but may be easily displaced therefrom by a blow against any portion of the bird.

The device preferably comprises said front wall 8 and back wall 9, and said back wall may be of equal height with said front wall but of greater width, so that when the opposite lateral edges 10, 11, respectively, are brought together and secured, as by

metal fasteners 12, 12, said back wall is bowed backwardly relatively to said front wall. This throws the scene on the front face of the back wall into perspective and provides a chamber between said walls.

For further maintaining said back wall in bowed relation to front wall 8, said front wall may be provided with flap 13 articulated to the upper edge of mid-opening 14 therethrough. Said flap 13, as shown in the positions of Figs. 2 and 3, has a rear curved edge 15 conforming to the curve of rear wall 9 when in bowed position, and the mid-portion of said curved edge is provided with tongue 16 projecting rearwardly therefrom for engagement with the edges of slot 17 through the upper mid-portion of back wall 9. If desired, an additional distending member for the bowed back wall may be employed, comprising double floor 18, 19. Said floor members may be formed integral with front wall 8. Floor member 19 is articulated to the lower edge 20 of wall 8, and the rear edges of said members 18, 19 are articulated at 21. The rear edges of said members 18, 19 are curved in approximate conformity with the curve of bowed back wall 9 and their line of articulation is relatively short. Floor member 18 extends forwardly and upwardly from line 21 and the forward edge of said member is provided with one or more tongues, as 22, for engagement with the edges of corresponding slots, as 23, through front wall 8. There is thus provided a floor for the device adapted to receive and hold birds and missiles which may fall behind wall 8.

Opening 14 through wall 8 may be rectangular and lower edge 24 thereof is preferably protected against undue wear from the birds by means of a shoe 7 preferably of metal. This shoe or rail may extend the full length of edge 24 and be secured thereto by some convenient means such as teeth 26 formed therefrom. Said shoe 7 is also efficient for reducing the friction of the bird claws on said edge 24, so that said birds may fall readily when struck.

Below edge 24, one or more openings, as 27, through wall 8 are provided for permitting the tails, as 6, of said birds to project forwardly of wall 8. Said projecting tails will therefore serve as a target as well as

the bodies of the birds above edge 24, and said openings facilitate the dismounting of the birds when hit.

I claim:

5. 1. In a device of the character described the combination of a front wall, a back wall, said back wall being of greater width than said front wall, means for removably securing together the lateral edges respectively of said walls whereby said back wall is bowed away from said front wall, and an opening through said front wall the lower edge of which is adapted for releasably supporting one or more images.
10. 2. In a device of the character described the combination of a front wall, a back wall, said back wall being of greater width than said front wall, means for removably securing together the lateral edges respectively of said walls whereby said back wall is bowed away from said front wall, an opening through said front wall the lower edge of which is adapted for releasably supporting one or more images, and an anti-friction protecting shoe secured to said lower edge of the opening through said front wall.
15. 3. In a device of the character described the combination of a front wall, a back wall, said back wall being of greater width than said front wall, means for removably securing together the lateral edges respectively of said walls whereby said back wall is bowed away from said front wall, an opening through said front wall the lower edge of which is adapted for releasably supporting one or more images, and a second opening through said front wall below said first mentioned opening adapted for receiving therethrough a portion of an image mounted on said lower edge of the first mentioned opening.
20. 4. In a device of the character described the combination of a front wall, a back wall, said back wall being of greater width than said front wall, means for removably securing together the lateral edges respectively of said walls whereby said back wall is bowed away from said front wall, an opening through said front wall the lower edge of which is adapted for releasably supporting one or more images, and a flap articulated to the upper edge of said opening and having means on its free edge for interlocking with coacting means on said back wall comprising a tongue on its free edge, and a slot in said back wall adapted for receiving said tongue, the free edge of said flap having a contour corresponding with the curve of the back wall when said wall is in bowed condition.
25. 5. In a device of the character described the combination of a front wall, a back wall, said back wall being of greater width than said front wall, means for removably securing together the lateral edges respectively of said walls whereby said back wall is bowed away from said front wall, an opening through said front wall the lower edge of which is adapted for releasably supporting one or more images, a floor articulated to the lower edge of said front wall, and means for maintaining said floor in operative relation to said walls, the rear edge of said floor being curved to correspond with the curve of said back wall when said wall is in bowed condition.
30. 6. In a device of the character described the combination of a front wall, a back wall, said back wall being of greater width than said front wall, means for removably securing together the lateral edges respectively of said walls whereby said back wall is bowed away from said front wall, an opening through said front wall the lower edge of which is adapted for releasably supporting one or more images, a double floor one member of which is articulated to the lower edge of said front wall and the other to the rear edge of said first member, and means on the front edge of said other member for interlocking with coacting means on said front wall, said two floor members at their rear edges being curved to correspond with the curve of said back wall when said wall is in bowed condition.
35. 7. In a device of the character described the combination of a front wall, a back wall, said back wall being of greater width than said front wall, means for removably securing together the lateral edges respectively of said walls whereby said back wall is bowed away from said front wall, an opening through said front wall the lower edge of which is adapted for releasably supporting one or more images, a flap articulated to the upper edge of said opening and having means on its free edge for interlocking with coacting means on said back wall comprising a tongue on its free edge, and a slot in said back wall adapted for receiving said tongue, the free edge of said flap having a contour corresponding with the curve of the back wall when said wall is in bowed condition.
40. 8. In a device of the character described the combination of a front wall, a back wall, said back wall being of greater width than said front wall, means for removably securing together the lateral edges respectively of said walls whereby said back wall is bowed away from said front wall, an opening through said front wall the lower edge of which is adapted for releasably supporting one or more images, an anti-friction protecting shoe secured to said lower edge of the opening through said front wall, a second opening through said front wall below said first mentioned opening adapted for receiving therethrough a portion of an image mounted on said lower edge of the first mentioned opening, and a flap articulated to the upper edge of said first mentioned opening having means on its free

edge for interlocking with coacting means on said back wall, the free edge of said flap having a contour corresponding with the curve of the back wall when said wall is in bowed condition.

9. In a device of the character described the combination of a front wall, a back wall, said back wall being of greater width than said front wall, means for removably securing together the lateral edges respectively of said walls whereby said back wall is bowed away from said front wall, an opening through said front wall the lower edge of which is adapted for releasably supporting one or more images, an anti-friction protecting shoe secured to said lower edge of the opening through said front wall, a sec-

ond opening through said front wall below said first mentioned opening adapted for receiving therethrough a portion of an image mounted on said lower edge of the first mentioned opening, a double floor one member of which is articulated to the lower edge of said front wall and the other to the rear edge of said first member, and means on the front edge of said other member for interlocking with coacting means on said front wall, said two floor members at their rear edges being curved to correspond with the curve of said back wall when said wall is in bowed condition.

In witness whereof, I hereby affix my signature this 5 day of May, 1924.

EDGAR M. CLARK.
